UNITED STATES PATENT OFFICE.

ELSWORTH E. QUAINTANCE, OF DENVER, COLORADO.

DESIGN FOR A TOY FIGURE.

No. 38,334.

Specification for Design.

Patented Dec. 4, 1906.

Application filed October 1, 1906. Serial No. 337,026. Term of patent 14 years.

To all whom it may concern:

Be it known that I, ELSWORTH E. QUAINTANCE, a citizen of the United States, residing in the city and county of Denver and State of Colorado, have invented a new, original, and ornamental Design for a Toy Figure, reference being had to the accompanying drawing, which forms a part of this specification.

My invention relates to a new, original, and ornamental design for a toy figure, said design being illustrated in the accompanying drawing, which is a side elevation of a figure showing my new design.

The figure is a side elevation of a toy figure.

I claim—

The ornamental design for a toy figure as shown.

ELSWORTH E. QUAINTANCE.
